UNITED STATES PATENT OFFICE.

ALLEN JOHNSTON, OF OTTUMWA, IOWA.

BALL-SWAGING MACHINE.

SPECIFICATION forming part of Letters Patent No. 748,612, dated January 5, 1904.

Application filed March 26, 1903. Serial No. 149,712. (No model.)

To all whom it may concern:

Be it known that I, ALLEN JOHNSTON, a resident of Ottumwa, Iowa, have invented a new and useful Improvement in Ball-Swaging Machines, which invention is fully set forth in the following specification.

This invention relates to a machine for swaging metallic balls, particularly hollow metallic balls, such as referred to in my Patent No. 698,707, of April 29, 1902, and in my application, Serial No. 10,149, filed April 4, 1902.

The principal object of the invention is to provide a machine for rapidly swaging balls on their different axes after they have been shaped into spherical form, thereby truing, condensing, and hardening the same.

A further object is to provide a machine which will be automatic in its operation, the balls being automatically fed to the dies one after another and automatically discharged therefrom after the dies have operated thereon for a predetermined time, these operations being repeated *ad infinitum* without necessitating action on the part of an attendant or operator.

These objects are accomplished and other advantages attained by machines constructed in accordance with my invention, one embodiment of which is shown by way of example in the accompanying drawings, wherein—

Figure 1 is a front elevation with parts broken away and in section. Fig. 2 is an end elevation from the left of Fig. 1. Fig. 3 is an end elevation from the right of Fig. 1. Figs. 4 and 5 are sectional views through one pair of dies and the block in which they are mounted. Fig. 6 is a detail view of a part of the feed-bar which serves to feed the balls to and discharge them from the swaging-dies. Fig. 7 is a sectional view through a part of the machine on line 7-7, Fig. 1. Fig. 8 is a sectional view through the driving-wheel and its clutch mechanism, and Fig. 9 is a detail of the shoe which throws the clutch mechanism out of operation.

1 is the principal framework of the machine, supported on a table 2 and comprising an obliquely-disposed plate 3, Fig. 7, having a longitudinal rib 4 extending entirely across the machine, on which rib are mounted the

several blocks in which the swaging-dies operate, as presently described.

5 is the main shaft of the machine, provided with two eccentrics 6 6, Figs. 1 and 7. 55

8 is a reciprocating slide or carrier extending across the front of the machine and working at its opposite ends in slideways 9. It is reciprocated by eccentrics 6 through two pitmen 10 10 and carries the upper or movable 60 dies of the several sets of swaging-dies.

Ten sets of dies are shown in the drawings; but as they all alike a description of one set will suffice.

11 is a block having flanges 12 and 13, which 65 bear, respectively, against the upper and lower edges of the rib 4, as clearly shown in Figs. 3 and 7. The block is secured in position by means of screws 14 14 and has a countersunk slot 15 in its front face through which the 70 operation of the dies upon a ball may be observed, the slot of course being considerably narrower than the diameter of the balls. The lower or fixed die 16, having a hemispherically-recessed face, is socketed and fixed in 75 the inner end of plug 17, which is screw-threaded into an opening in the block 11. A plunger 18, working in a central opening in the plug 17, carries a pin 19, adapted to be reciprocated in and projected through an 80 opening through the fixed die 16 to dislodge the ball in case it sticks in said die and to cause the ball to change its position in the dies in the manner hereinafter described.

20 is the movable die, socketed and fixed in 85 the inner end of a sleeve 21, adapted to reciprocate in an opening in block 11. At its upper end sleeve 21 is screw-threaded into an opening in the frame 8, the screw-threaded opening being formed in part in a cap 22, secured to said frame by screws 23 23, Fig. 1. Sleeve 21 is securely clamped in the desired position by tightening-screws 23 to cause cap 22 to tightly grip the sleeve. Plunger 24, working in sleeve 21, carries a pin 25, working 90 in a central opening through fixed die 20 and adapted to be reciprocated in and projected through said opening to disengage the ball from the upper die in case it sticks therein. 95

26 is a ball feed and ejector bar extending 100 entirely across the machine and common to all of the sets of dies. It is located partly in

a longitudinal groove 27 in the rib 4 and partly in a transverse groove 28 across the under faces of blocks 11. Said bar 26 carries a roller 29, working in a cam-groove 30 of wheel 31, whereby it is reciprocated back and forth to discharge swaged balls from the dies and to feed unswaged balls thereto, as presently described. It has at one edge a series of notches 32, Fig. 6, one for each pair of dies, which notches in the normal position of the ball are brought into alignment with the several sets of dies, which latter work in the notches, as clearly shown in Fig. 4.

The balls to be swaged are conveyed to the dies through tubes 40, which are open or slotted at one side, so that the passage of the balls therethrough can be observed by the operator. There is a tube 40 for each set of dies connected at its lower end to an opening 41, intersecting groove 28 in block 11. The lowermost ball of the column of balls within each tube 40 bears against bar 26 when said bar is in its normal position. Conveyer-tubes 40 connect at their upper ends with a ball-hopper 45, through which rock-shaft 46, having depending agitator-arms 47, extends. Said shaft is oscillated, by means presently described, to move the agitator-arms 47 (of which there is one for each conveyer-tube 40) back and forth over the opening leading from the hopper into the tubes, the purpose being to insure proper feeding of the balls from the hopper into the tubes.

The plungers 24 and pins 25, carried thereby, are operated upon each upward reciprocation of plate 8 by studs 50, screwed into plate 3, the heads of the studs being respectively located in recesses 51 in slide 8. Heads of these studs lie in the path of plungers 24, so that the upper ends of said plungers strike the studs upon the upward movement of the frame 8, thereby projecting the pins 20 through the upper or movable dies and dislodging the balls in case they stick in and are carried upwardly by said dies.

The plungers 18 and their pins 19 are operated upon each upward movement of the frame 8 through the following mechanism: 55 is a bar extending across the front of the machine below block 11 and joined to frame 8 by connecting-bars 56 56. Two bolts 57 57, secured in bar 55, project upwardly and pass loosely through a parallel contact-bar 58. Springs 59 59, interposed between bars 55 and 58, act to normally hold the bars separated by pressing the bar 58 upwardly into contact with the heads of the bolts, but permitting it to be moved toward bar 55 when the tension of the springs is overcome. Dogs 60 60 are located at opposite sides of the frame of the machine and normally held in the position shown in Fig. 1 by flat springs 61 61. Upon upward movement of the frame 8, carrying with it the bars 55 and 58, the latter before coming into contact with the lower ends of the plungers 18 of the several sets of dies is engaged at its opposite ends by a

shoulder 62 on each dog 60, thereby forcing bar 58 downwardly against the bar 55 and compressing the springs 59. Upon further upward movement of the parts, however, each end of bar 55 engages an incline 63 on the dogs 60, moving them outwardly on their pivots against the tension of springs 61 until the shoulders 62 on the dogs are removed from the path of the bar 58, thereby releasing said bar and permitting the springs to move the same upwardly into contact with the plungers 18 by a quick stroke, the effect of which is to discharge the balls from the lower dies, throwing them upwardly in the space between said lower die and the then uplifted upper die. In rolling back along the inclined surface of the wall of the opening in block 11 (which constitutes a ball-retaining wall or inclosure) to the hemispherical recess in the lower die the balls turn over several times, coming to rest in the lower die in a different axial position to that occupied upon the previous stroke of the dies, so that for each stroke made by the latter the balls assume a different position.

I will now describe the power mechanism for operating the several parts of the machine, the means for automatically and intermittently throwing the slide carrying the movable dies out of operation and for intermittently throwing the feed and ejector bar into operation during the intervals when said dies are not operating.

70 is a driving-wheel loose on shaft 5 adjacent to a disk 71, which is keyed to said shaft, Fig. 8. In order to connect the driving-wheel 70 with shaft 5 to operate the dies through mechanism already described, I provide the following clutch mechanism: 72 is a spring-actuated clutch-bolt housed in the hub of wheel 70, the tension of the spring tending to normally engage said bolt in a notch or recess 73 in the adjacent face of disk 71, thereby locking these parts together, and hence driving the shaft 5. It is necessary, however, to arrest the operation of the movable die members in discharging swaged balls from and feeding fresh unswaged balls to the dies. To effect this, means are provided for throwing the clutch-bolt out of engagement with the notch in disk 71 at the proper time and to hold it in its retracted position until the ejecting and feed movements of the bar 26 have been completed. As shown herein, this means comprises a shoe 80, carried at the upper end of a rod 81 and acting to move the clutch-bolt out of engagement with the notch in disk 71, and a detent 84, acting to engage and hold the clutch-bolt in this position for a proper period of time. Shoe 80 has a concaved edge 82, adapted to bear against the peripheral surface 83 of the disk 71. When the shoe is withdrawn from contact with disk 71, the curved edge 82 thereof is brought to such position as to engage lug 87 on the detent 84 as the latter rotates with wheel 70, thereby withdrawing said detent

from engagement with the lug 85, freeing the bolt for engagement with notch 73, thereby again locking wheel 70 into engagement with the shaft 5. Proper movement is imparted to the shoe 80 through its rod 81 by the following means: The forked end of an arm 90 engages a pin 91 on rod 81. The other end of said arm is secured in a transverse opening through the projecting end of a rock-shaft 92 by a set-bolt 93. An arm 94 is secured in the transverse opening in the opposite end of shaft 92 (which extends from one side of the machine to the other) by means of a set-bolt 95. A tooth 96 on the free end of arm 94 normally (during the operation of the dies) bears upon the smooth peripheral surface of the flange 97 on the wheel 31, the tooth being caused to bear upon this flange through the tension of spring 98 around rod 84, Figs. 3 and 8, said spring bearing at one end against a bracket 99, secured to the framework, and at its other end against a collar 100, fixed on said rod. The tendency of this spring is to lift the shoe 80 into position to disengage the clutch-pawl from the disk 71; but this movement is impossible so long as the tooth 96 bears against the peripheral surface of the flange 97; but, as shown in Fig. 2, said flange is cut away at 101, so that when the tooth 96 drops into the space thereby provided the spring 98 throws the shoe up into position to throw the clutch mechanism out of operation. It remains out of operation until the rotation of wheel 31 (in a manner presently described) brings the inclined end 102 of the flange 97 into contact with tooth 96, again moving said tooth up onto the peripheral surface of the flange, imparting a corresponding movement to the shaft 92, arm 90, and rod 81 sufficient to withdraw the shoe from the position in which it prevents engagement of the clutch-bolt with the notch in disk 71.

Wheel 31, which, as we have seen, not only controls the operation of the clutch mechanism, but effects the operation of the feed and ejector bar 26 by its cam-groove 30, is intermittently rotated through the following connections: A rock-shaft 105, extending from one side of the machine to the other, has at one end an arm 106, carrying a roller 107, which bears against the inner eccentric surface 108 of the flange of wheel 70, so that upon each rotation of said wheel an oscillatory movement is imparted to the shaft through the roller and arm. At its other end shaft 105 carries an arm 109, which has a pawl 110 pivoted to its outer end and engaging ratchet-teeth 111 to intermittently rotate wheel 31. The rod 109 in the position shown in Fig. 2 is at the limit of its movement in one direction, the ratchet 110 having just dropped into engagement with one of the teeth. As the wheel 70 rotates it acts on the roller 107 to move arm 109 and its ratchet toward the right, the wheel 31 being rotated in the same direction a distance of one tooth. This intermittent movement of the wheel 31 con-

tinues, of course, so long as wheel 170 is rotated and also during the time that the clutch mechanism is thrown out of operation. 70

An arm 112, Figs. 2 and 3, on the end of shaft 46 bears against the eccentric inner surface of the flanged wheel 70 to oscillate said shaft and its depending arms in one direction, movement in the opposite direction 75 being effected by springs 113.

The operation of the entire machine, briefly described, is as follows: As shown in Figs. 1, 2, and 3, the clutch is in position to connect wheel 70 with shaft 5. Consequently a stroke 80 is imparted to the upper die members upon each rotation of said wheel. After one or more such strokes, during which the wheel 31 is advanced (from the position shown in Fig. 2) in the direction of the arrow, the tooth 96 85 drops off the peripheral surface 97 of wheel 31 into the space 101, the effect of which is to throw the clutch out of operation in the manner already described, the operation of these parts being so timed that the upper die 90 members will come to rest in an elevated position, such as shown in Fig. 5, the balls being held up out of the hemispherical recesses in the lower dies by plungers 18 and their pins 19. Thereupon the cam portion of groove 95 30 in wheel 31 comes into operation upon roller 29 to move the feed and ejector bar 26 (which carries with it in its notches the swaged balls) to the left, Figs. 1, 4, and 5, until the swaged balls are finally delivered to the discharge 100 openings 115, formed partly in each of the adjacent edges of the blocks 11. In this discharge movement of the bar the presence of the swaged balls in the notches prevents the lowermost unswaged balls in the tubes 40 105 from dropping into said notches; but upon the return movement of said bar to the right the lowermost unswaged ball in each tube drops into its appropriate then empty notch of the bar and is delivered to the proper set of 110 dies. Thereupon the inclined end 102 of the flange 97 of wheel 31 operates upon the tooth 96 of arm 94 to release the clutch mechanism, again throwing the swaging-dies into operation, said operation continuing until the 115 clutch is again thrown out of operation in the manner described.

What I claim is—

1. In a machine for swaging and truing balls, dies for acting on the balls, means actuating one of the dies and subjecting each ball to a plurality of strokes, and automatically operating ball feeding and discharging means for delivering each ball between the dies and for removing it therefrom after a plurality of 120 strokes of the dies.

2. In a machine of the kind described, the combination with dies for acting on the balls, means actuating one of the dies and subjecting each ball to a plurality of strokes, and means for intermittently changing the axial position of the ball with relation to the dies during the making of said plurality of strokes. 130

3. In a machine of the kind described, the

combination with dies for acting on the balls, means actuating one of the dies and subjecting each ball to a plurality of strokes, and automatically-operating means for intermittently changing the axial position of the ball with relation to the dies during the making of said plurality of strokes.

4. In a machine of the kind described, the combination with dies for acting on a ball by a plurality of strokes, automatically-operating feeding and discharging means for delivering the ball between the dies and for removing it therefrom after it has been acted upon, and automatically-operating means for intermittently changing the axial position of the ball with relation to the dies.

5. In a machine of the kind described, the combination with dies for acting on the balls, means actuating one of the dies and subjecting each ball to a plurality of strokes, automatically-operating feeding and discharging means for delivering the ball between the dies and for removing it therefrom after it has been acted upon, and automatically-operating means for intermittently changing the axial position of the ball with relation to the dies.

6. In a machine of the kind described, the combination with dies for acting on the balls, means actuating one of the dies and subjecting each ball to a plurality of strokes, and means operating in conjunction with each die and after each stroke of the dies to disengage the ball therefrom and to change the axial position of the ball in the dies before the next succeeding stroke.

7. In a machine of the kind described, a lower and an upper die, a ball-retaining wall or inclosure around said dies preventing escape of the ball when the dies are separated, a plunger associated with the lower die, and means automatically operating said plunger to disengage the ball from the lower die and throw it upwardly in the space within the ball-retaining wall or inclosure while the dies are separated after each stroke thereof.

8. In a ball swaging and truing machine, the combination of two dies, actuating means reciprocating one of the dies and subjecting each ball to a plurality of strokes, automatically-operating means for intermittently arresting the operation of said actuating means after a plurality of strokes of the dies, and ball discharge and feed means operating automatically while the die-actuating means are at rest to discharge the ball acted upon from the dies and to deliver another ball thereto.

9. The combination with dies for acting on a ball, a hopper for balls to be acted upon by the dies, and ball-feeding means for delivering the balls one after another to the dies and for discharging each ball from the dies before the next succeeding ball is delivered thereto from the hopper.

10. The combination with dies for acting on balls, means actuating one of the dies and

subjecting each ball to a plurality of strokes, a hopper for balls to be acted upon by the dies, and ball-feeding means for delivering the balls one after another from the hopper to the dies and for discharging each ball from the dies before the next succeeding ball is delivered thereto from the hopper.

11. The combination with a plurality of sets of dies for acting upon balls, and means common to all of the sets acting by one movement to introduce balls between the dies and by another movement to remove the balls after the operation of the dies.

12. The combination with a plurality of sets of dies for acting upon balls, a ball feed and ejector bar common to all of the sets of dies, and means automatically and intermittently operating said bar to both feed balls to and eject them from the dies.

13. The combination with a plurality of sets of dies for acting upon balls, a ball-hopper, a ball passage or tube leading from said hopper to each set of dies, and ball-feeding means consisting of a movable bar having openings therein and common to all of the sets of dies, said bar working in proximity to the sets of dies and to the ball-passages, and means automatically operating said bar to simultaneously deliver a ball from each of the ball-passages to the sets of dies respectively.

14. The combination with a plurality of sets of dies for acting upon balls, a ball-hopper, a ball passage or tube leading from said hopper to each set of dies, and ball ejecting and feeding means consisting of a movable bar having openings therein and common to all of the sets of dies, said bar working in proximity to the sets of dies and to the ball-passages, and means automatically operating said bar to simultaneously deliver a ball from each of the ball-passages to the sets of dies respectively.

15. In a machine of the kind described, the combination with dies for acting on a ball, ball feeding and discharging means consisting of a reciprocatory bar having an opening therein acting upon the feed movement of the bar to receive a ball from a ball-supply passage and to deliver it between the dies which in acting upon the ball operate in the opening whereby said opening acts upon the discharge movement of the bar to withdraw the ball from between the dies and deliver it to a discharge-opening, and means for automatically imparting said feed and discharge movements to the bar.

16. The combination with a plurality of sets of dies, for acting upon balls, a ball-supply passage or tube leading to each set of dies, ball feeding and discharging means consisting of a reciprocatory bar common to all of the sets of dies and having openings therein, one corresponding to each set, acting upon the feed movement of the bar to receive balls from the corresponding ball-feed tubes and

to deliver them between the dies which in
acting upon the ball operate in the openings
whereby said openings act upon the discharge
movement of the bar to withdraw the balls
from between the dies and deliver them to
discharge-openings, and means for automatically
imparting said feed and discharge
movements to the bar.

In testimony whereof I have signed this
specification in the presence of two subscr- to
ing witnesses.

ALLEN JOHNSTON.
